UNITED STATES PATENT OFFICE.

EDWARD A. WHALEN AND OTTO R. ILLING, OF NEW YORK, N. Y.

CRUTCH.

1,283,387.

Specification of Letters Patent.

Patented Oct. 29, 1913.

Application filed June 8, 1913. Serial No. 233,952.

To all whom it may concern:

Be it known that we, EDWARD A. WHALEN, and OTTO R. ILLING, citizens of the United States, residing at Bronx, in the county of 5 King and State of New York, have invented certain new and useful Improvements in Crutches, of which the following is a specification.

This invention relates to crutches, and 10 more particularly to a crutch of the cushion type provided with means for absorbing or cushioning jars incident to the use of the crutch.

One of the main objects of the invention 15 is to provide a crutch of the character stated of simple construction and operation in which the arm piece upon which the user's weight is usually placed is resiliently supported so as to obtain a cushioning effect. 20 A further object is to provide simple and efficient means for supporting the arm piece and for permitting proper movement thereof toward and away from the body portion of the crutch. Further objects will appear, 25 from the detailed description.

In the drawings:

Figure 1 is a fragmentary side view of a crutch constructed in accordance with our invention,

30 Fig. 2 is a section taken substantially on line 2—2 of Fig. 1,

Fig. 3 is a fragmentary section taken through the upper portion of the body of the crutch and the adjacent portion of the 35 supporting frame.

The body of the crutch may be of any suitable or standard construction being provided with the side bars 1 and 2 and top bar 3. This top bar supports lower element or bow 4 of an elliptical spring 5 the 40 ends of which are hingedly secured to the ends of an upper bow 6 by hinge pins 7. A securing screw 8 is inserted through lower bow 4 of the spring and is threaded into top bar 3 of the crutch. Two pins 9 are inserted through openings provided through bow 4 equi-distant from screw 8 and project into alined recesses provided in top bar 3, these pins 9 serving to prevent rotary movement of bow 4 about the screw.

Screw 8 is provided with an enlarged head 10 of cylindrical shape which projects above the central horizontal portion 4^a of bow 4. Head 10 of screw 8 is in vertical alinement 55 with a similar head 11 of a screw 12 which

is inserted through the center of the horizontal central portion 6^a of the upper bow 6 and threaded into a shoulder block 13. The two heads of the screws constitute centering elements or studs about which are 60 mounted the end portions of a coiled spring 14. This spring co-operates with the elliptical spring 5 to maintain the shoulder block 13 in raised position away from the top bar 3 of the body of the crutch. The 65 screws in addition to securing the elliptical spring 5 to the top bar of the body of the crutch and to the shoulder piece 13 also serve in the manner specified as means for securing the coil spring 14 in operative position. The upper bow 6 of the elliptical spring is also provided with spaced pins 9^a corresponding to the pins 9 of the lower bow which are carried by the horizontal portion 6^a and fit tightly into the shoulder piece 13 70 so as to prevent relative rotary movement between the shoulder piece and the spring.

In use, the springs 5 and 14 act to maintain the shoulder piece away from the top bar 3 of the body of the crutch. When the 80 user's weight is thrown upon the shoulder piece 13, this member will be moved toward the top bar of the crutch, this movement being retarded by the springs thus providing a cushioning effect which greatly reduces the 85 jars and jolts incident to the use of a crutch. As will be noted, the shoulder piece 13 and the springs for supporting the same may be readily applied to a crutch body of standard construction thus producing a device of 90 efficient but simple and cheap make which may be manufactured at small cost.

The foregoing description and the drawings have reference to what may be considered the preferred or approved form of our 95 invention. It is to be understood that we may make such changes in construction, and arrangement, and combination of parts, materials, dimensions, et cetera, as may prove expedient and fall within the scope of the 100 appended claims.

Having thus fully described our invention, what we claim as new and desire to secure by Letters Patent, is:—

1. In a crutch, a body provided with a top 105 bar and side bars secured thereto, a substantially elliptical spring secured to the top bar on the upper face thereof, a shoulder block mounted on said spring for movement toward and away from the top bar, and an 110

expansion spring confined between the bows of said elliptical spring.

2. In a crutch, a body provided with a top bar and side bars secured thereto, a substantially elliptical spring secured to the top bar on the upper face thereof, a shoulder block mounted on said spring for movement toward and away from said top bar, the upper and lower bows of said elliptical spring each provided with a straight portion intermediate its ends, the straight portion of the lower bow resting upon the top bar and the straight portion of the upper bow receiving the shoulder block, and an expansion spring confined between the straight portions of the bows of said elliptical spring.
3. In a crutch, a body provided with a top bar and side bars secured thereto, a substantially elliptical spring secured to the top bar on the upper face thereof, a shoulder block mounted on said spring for movement toward and away from said top bar, an expansion spring confined between the bows of said elliptical spring, and means for securing the elliptical spring to the said shoulder block and the top bar of the body of the crutch, said means being also adapted to

maintain the expansion spring in operative position.

4. In a crutch, a body provided with a top bar and side bars secured thereto, an elliptical spring having its lower bow secured to the top bar on the upper face thereof, a shoulder block mounted on the upper bow of said spring, securing screws inserted through the respective bows of the spring and threaded into the said top bar and shoulder block so as to secure the spring thereto, said screws being in vertical alinement and having enlarged cylindrical heads to form centering members for a coiled expansion spring, and a coiled expansion spring confined between the bows of said elliptical spring and having its end portions mounted about the heads of said screws so as to be retained in operative position thereby.

In testimony whereof we affix our signatures in presence of two witnesses.

EDWARD A. WHALEN,
OTTO R. ILLING.
